RADIO

Minoru Arai, 40, 1-Cho, Nanshocko, Sakai, Osaka, Japan

Filed May 6, 1959, Ser. No. 55,795

Term of patent 14 years

(Cl. D56—4)

Fig. 1 is a perspective view of a radio, showing my new design; and

Fig. 2 is a perspective view taken from a point diametrically opposite to the view shown in Fig. 1.

More particularly this design includes a circular wafer shaped control knob extending above one pole of a spherical globe-like exterior; a raised slotted band extending between opposing poles on said exterior with a slideable turner disposed in said slot; a raised equatorial band extending around said exterior; a hemispherical base supporting said globe-like member; and a speaker

grill formed in said exterior adjacent said base all as shown.

I claim:

The ornamental design for a radio, substantially as shown and described.
